INVENTOR:
George B. Adams.

BY Campbell & Co. ATTYS.

UNITED STATES PATENT OFFICE.

GEORGE B. ADAMS, OF IRVINGTON, NEW JERSEY.

SCARF-HOLDER.

SPECIFICATION forming part of Letters Patent No. 397,955, dated February 19, 1889.

Application filed September 15, 1888. Serial No. 285,488. (No model.)

To all whom it may concern:

Be it known that I, GEORGE B. ADAMS, a citizen of the United States, residing at Irvington, in the county of Essex and State of New Jersey, have invented certain new and useful Improvements in Scarf-Holders; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

This invention consists in a new and improved fastening device by means of which a neck tie or scarf can be firmly held in place and be removed with facility and ease when required, the object of the invention being to provide a simple and cheap device, which is ornamental as well as useful, and which may be applied to grasp the tie and bosom-band of the shirt separately, so as to prevent any upward displacement of the tie or scarf.

In the drawings herewith accompanying, in which similar letters of reference indicate corresponding parts in each of the views, Figure 1 is a side elevation of my improved scarf-fastener, showing the relative positions of the clamping-head or button and the claw-plate when in their clamped or locked position. Fig. 2 is a view similar to Fig. 1, representing the head in section and in its unlocked position. Fig. 3 is a side elevation of the device, illustrating the relation of the parts before the insertion of the shirt or bosom-band and the tie or scarf. Fig. 4 represents a blank, from which the body portion or base-plate of the holder is struck up, and to which the claw-plate or arm is pivoted. Fig. 5 is a perspective view of the claw-plate. Figs. 6 and 7 represent side elevations of several different constructions of the device, and Fig. 8 is a sectional view of Fig. 7. In Figs. 9 and 10 is shown still another form of construction, the views thereof being shown in section. Fig. 11 illustrates the manner of arranging the relative parts of the device when applicable to be used as a garment-supporter.

The essential features of the device illus-

trated in the above-described views are a base-plate, *a*, made from spring metal, provided with an arm, *a'*, said arm or end extending up into a chambered head or button, *b*, and engaging with a spring, *b'*, in said head, thus pivotally securing the head or button to the base-plate *a*. L-shaped pieces or arms *a²* are "stamped up" from the plate *a* and turned up to form flanges, between which a claw-plate or clamping-lever, *c*, is hinged or pivotally secured. The hinged end *c'* may be provided with teeth *c²* to grasp the bosom-band of the shirt when the same is inserted beneath said claw-plate and the base-plate of the fastener.

In applying the device to use, the bosom-band of the shirt is thrust between the base-plate *a* and the arms *a²*, and the claw-plate, which had previously been sprung or turned upward, as indicated in Fig. 3, is then brought down upon the bosom-band, thus clamping the band firmly between the base-plate *a* and the teeth *c²* of the claw-plate. This being accomplished, the scarf is then brought into position between the upper edges, *a³*, of the arms *a²* and the hinged or pivoted button *b* and the button brought parallel, or approximately so, with the arms *a²*, so that the tooth *b²* of the button or head indents itself into the outer surface of the scarf, while the upper edges, *a³*, of the arms *a²* of the base-plate in like manner project into the inner side of the scarf, and thereby prevent any upward displacement of the same.

If desirable, the upper edges of the arms *a²* may be provided with teeth *a⁴* to more firmly grasp and hold the scarf in position.

In the construction shown in Figs. 7 and 8 the head or button may be pivoted directly to the claw-plate, instead of to or on the base-plate *a*, as indicated in Figs. 1, 2, and 3. When it is desirable to use this latter form of construction, the base-plate *a* is made from a continuous piece of spring metal bent into an upper and lower plate, as shown in Figs. 7 and 8, the upper plate being provided with two upright flanges, *a²*, similar to those shown in Fig. 1, &c., between which is pivoted a claw-plate, *c*, the end *c'* of which passes

through and projects down into and beneath a slot, a^5 , in the upper plate, and thus engaging with the bosom-band, which has been inserted between the upper and lower base-
5 plates, as will be understood from Fig. 8.

In Figs. 9 and 10 is shown another form of construction in which the claw-plate is hinged to posts formed integrally on the lower base-plate, a^5 , and the end c' of the claw-plate en-
10 gaging directly with the upper plate, a^6 . In this construction the bosom-band is not in-
15 serted between the claw-plate and the upper plate, a^6 , as in Fig. 8, but the plates or jaws a^6 and a^7 are made to grasp the bosom-band, and the claw-plate c being brought down upon
20 the upper plate, a^6 , said plate is forced down upon the lower plate and the bosom-band firmly held between the jaws. The scarf is then placed on the claw-plate, and the head or button brought to bear down upon the same, holding the scarf in position.

The device represented in Fig. 11 is meant to be used as a garment-supporter. In said view the upper plate is bent at a'' and made
25 to pass under the lower jaw or base-plate at a^{12} . When the claw-plate c is turned down, the end c' of said plate rides on the jaw a^7 , and the waistband of a pair of pants having
30 been inserted at a^{12} , the device is thus firmly secured thereto, the band of the wearer's drawers being inserted between the button b and the claw-plate c in the manner described above.

The features in the above-described invention are of considerable importance, as the scarf may be removed from the device without removing the latter from the bosom-band of the shirt when in wearing position by simply raising the head or button b , which seizes
35 the scarf and holds the same in position, and withdrawing the same from the holder, which remains attached to the shirt as long as the shirt is intended to be worn.

Having thus described my invention, what
45 I claim is—

1. In a scarf-holder, the combination, with the body portion consisting of clamping-jaws having arms on each side thereof, of a claw-plate pivotally secured between said arms
50 and co-operating with said jaws to grasp the bosom-band of a shirt, a head or button pivotally arranged on an arm extending up from said body portion, and a spring operating to cause the holding-contact of said head and body portion, for the purposes set forth.

2. In a scarf-holder, the combination, with

the body portion consisting of holding-jaws to grasp the bosom-band of a shirt, of a head or button secured to said body portion by means of an arm projecting up into the upper clamping-head, which consists of a casing, as set forth, and engaging with a spring arranged in said casing and operating to cause the holding-contact of the head and body portion, for the purposes set forth. 60

3. In a scarf-holder, the combination, with the body portion consisting of clamping-jaws having arms on each side thereof, of a claw-plate pivotally secured between said arms and co-operating with said base-plate to grasp the 70 bosom-band of a shirt, and a head or button arranged on the opposite end of the claw-plate, said head consisting of a casing, as set forth, into which the end of the claw-plate extends and engages with a spring arranged in said 75 casing and operating to cause the holding-contact of the head and body portion.

4. A scarf-holder composed of a body portion consisting of holding-jaws having arms on each side thereof, a claw-plate pivotally secured at one end thereof between said arms to grasp the bosom-band of a shirt, and a head or button pivotally arranged on said claw-plate at the opposite end thereof, for the 80 purposes set forth. 85

5. In a scarf-holder, the combination, with the body portion consisting of a pair of jaws, of a claw-plate hinged to one of said jaws, so as to act upon the other jaw to grasp the bosom-band of a shirt, and a head or button 90 pivotally arranged on the opposite end of said claw-plate, for the purposes set forth.

6. In a scarf-holder, the combination, with the body portion consisting of a pair of jaws, of a claw-plate hinged to one of said jaws, so 95 as to act upon the other jaw to grasp the bosom-band of a shirt, a head or button pivotally arranged on the opposite end of said claw-plate, said head consisting of a casing, as set forth, into which the end of the claw-plate extends and engages with a spring arranged in said casing and operating to cause the holding-contact of the head and body portion, substantially as and for the purposes set forth. 100

In testimony that I claim the invention set forth above I have hereunto set my hand this 12th day of September, 1888.

GEO. B. ADAMS.
